UNITED STATES PATENT OFFICE.

JOHN R. BENOUGLE, OF DETROIT, MICHIGAN, ASSIGNOR, BY MESNE ASSIGNMENTS, TO
KELVINATOR CORPORATION, OF DETROIT, MICHIGAN, A CORPORATION OF MICHIGAN.

REFRIGERATOR.

Application filed May 21, 1921. Serial No. 471,817.

This invention relates to refrigerators and more particularly to the type of refrigerators that are mechanically operated and in which a liquid is employed as a cooling or heat conveying medium.

An object of the invention is the provision of improved means for opening and closing the cooling fluid valve simultaneously with the starting and stopping, respectively, of the motor.

Another object of the invention is the provision of improved means for automatically stopping the motor when the pressure of the cooling fluid falls below a predetermined minimum and for returning it to its normal control when the cooling fluid pressure again becomes normal.

With these and other objects and advantages in view which will appear as the description proceeds, the invention consists in the novel construction and arrangement of parts, hereinafter described, particularly pointed out in the appended claims, and illustrated in the accompanying drawing in which,

The figure is a diagrammatic view of the operating mechanism of a mechanical refrigerator, together with my improvements thereon.

On the drawing, the refrigerant system, which consists of the compressor 5, the condenser 6, vaporizer 7, and attendant pipes and valves are adapted to be operated by the motor 8, and may be of any suitable construction, such for example, as that shown and described in my application, Serial No. 448,381, filed February 28, 1921.

Any suitable refrigerant may be employed, such, for instance, as sulphur dioxide (SO_2).

The refrigerant vapor is drawn through the pipe 12 from the vaporizer into the compressor where it is compressed and forced into the condenser dome 10. After being condensed by the water flowing through the cooling or condenser coil 11, it is forced in liquid form up through the pipe 9, into the header or expansion chamber 13, thus completing the circuit.

The expansion tank 13 may, if desired, be arranged in the upper portion of a brine tank 14, which contains any suitable liquid that has a low freezing point, such as a solution of calcium chloride (CaCl_2). The expansion tank 13 is adapted to be partially or

entirely immersed in the brine. The expansion tank may be provided with expansion tubes (not shown) which are adapted to be immersed in the brine.

The motor employed is one that is suitable for the motor power available. The motor shown is an electric one, and is controlled by any suitable thermally operated switch-controlling mechanism. One form of switch-controlling mechanism for this purpose is shown diagrammatically in the figure. A pipe 15 is connected to a source of pressure. It may be connected directly to the expansion chamber 13, or, if preferred, it may be secured as indicated on the drawing to a thermostatic bulb (not shown). This bulb is secured in the brine tank and contains a suitable fluid that is responsive to the temperature of the brine. The other end of the pipe 15 is connected to the lower end of a corrugated longitudinally extensible member or bellows 16 seated on the base plate 17 of the controller box. A cap 18 engages the upper end of the bellows 16 and is provided with a laterally extending arm 19, the outer end of which is pivotally connected to the base plate 17 by means of the link 20. The cap 18 is provided with a bearing 21 in which the knife edge 22 on the lower side of the lever 23 is adapted to engage. The upper end of the lever 23 is provided with a knife edge 24, located inwardly of the knife edge 22, which is adapted to engage a bearing 25 carried by the upper plate 26 of the controller box. A weight 27 is adjustably mounted on the outer end of the lever 23 and serves to set the control so that it will operate at any desired or given temperature. The inner end of the lever 23 is pivotally connected to the arm 28. The arm 28 is provided with a shoulder 29 which permits the arm to move upwardly relatively to the lever 23, but prevents its moving in the opposite direction beyond a position in alignment with the lever 23. A weight 30 is adjustably mounted on the outer end of the arm 28. Pivotally attached to the intermediate portion of the arm 28 is a link 31, which is adapted to operate an electric switch.

The electric switch employed may be of any suitable or known form, the one shown being of the "snap switch" type. It consists of two conductor posts 32 and 33 which are adapted to be bridged by the contact plate 34

carried by light springs 35. The free ends of the springs 35 are connected to the inner ends of a projection 36 rigidly connected to the lever 37. The lever 37 is pivoted by means of a knife edge to the post 38. A lever 39 has one end pivotally connected to the post 38 by means of a knife edge and its free end pivotally connected to the link 31. Two springs one of which is shown at 40 connect the outer ends of the levers 37 and 39 in such a manner that when the levers are moved in either direction past "dead center" the springs will cause them to move with a quick action to the limits of their movements. A latch 41 is provided with a hook 42 which extends through a slot 43 in the lever 37 and is adapted to limit the upward movement of said lever. The latch 41 is provided with a notch 44 which is adapted to engage the lever 37 at the outer edge of the slot 43 when the levers 37 and 39 are at the lower limit of their movement. The notch 44 is adapted to hold the lever 37 in lowered position until the lever 39 is elevated to such a position that the extension 45 thereon engages the projection 46 on the latch and moves the same forwardly against the tension of the spring 47, thus releasing the lever 37 and permitting the springs 40 to snap the same upwardly to the limit of its movement.

In the operation of the device, when the thermostat rises above a predetermined temperature the pressure therein will increase due to the expansion of the vapor therein and will cause an elongation of the bellows 16, which, in turn, will cause an upward movement of the outer end of the lever 23, with a corresponding lowering of the weighted lever arm 28, thus lowering the link 31. The lowering of the link 31 will carry the lever 39 downward past "dead center" and the springs 40 will snap the contact plate 34 in engagement with the conductor posts 32 and 33, thus closing the circuit and starting the motor.

Any suitable system of wiring may be employed. As shown diagrammatically in the figure, the current may be traced through the hand switch 48, wire 49, conductor post 33, contact plate 34, post 32, wire 50 to one terminal of the motor 8, back through the other terminal of the motor and the wire 51 to the switch 48.

In refrigerators of the compression type, it is necessary to employ a cooling fluid, usually water, to absorb and conduct away the heat of the compressed refrigerant vapor in order to condense the same. In devices that are automatically controlled the compressor is operated intermittently and hence it is not necessary that the cooling fluid run continuously. It is the usual practice in such devices to operate the water valve by mechanism controlled by pressure within the condenser; the mechanism being so arranged and

adjusted that the water valve will not begin to open until after the motor starts and the compressor has built up the pressure within the condenser to a predetermined limit. In order to prevent the opening of the water valve in these pressure controlled devices and the consequent loss of water, while the motor is at rest, it is necessary to set the pressure limit at a point slightly above the pressure corresponding to the environment temperature at the hottest season of the year; and since the compressor is not heat insulated, this limit is necessarily determined by the highest probable room temperature. In other words, in order to prevent the opening of the valve and the consequent loss of water while the compressor is at rest, it is necessary to set the pressure limit for the control at a point greatly in excess of what is necessary to condense the refrigerant vapor at the temperature of the cooling fluid, and when set at this high limit, it will, of course, be necessary for the compressor to operate at all times against this high pressure which very materially decreases the efficiency of the apparatus as well as adding to its cost of operation.

By arranging the water valve so that it will be opened and closed simultaneously with the starting and stopping of the motor, the pressure against which the compressor must work would be only what is necessary to condense the refrigerant vapor at the temperature of the water flowing through the condenser, and since this would be much less than that under the above system,—in fact, only about one half as much,—it follows that this arrangement is cheaper to operate and much more efficient than devices having pressure control.

The above function is accomplished by the mechanism which will now be described.

A pipe or water conduit 52 is adapted to be connected to a water main and to one end of the condenser coil 11. A pipe 53 is connected to the other end of the condenser coil 11 for conducting the water to the sewer. A valve 54 is provided for controlling the flow of water through the pipe 52. This valve is operated by a solenoid 55 against the tension of a spring 56. The solenoid is energized through the conductors 57 and 58 which as shown are arranged in shunt with the motor, but may of course be connected in series with the same. When the circuit is closed, the solenoid operates to open the valve and when the circuit is open the spring 56 closes the valve.

It sometimes happens that for one reason or another, the flow of water through the pipe 52 is wholly or partially interrupted and in which event the pressure within the condenser would soon become excessive unless some provision is made for stopping the motor.

One form of mechanism for accomplishing

this function will now be described. The pipe 52 is provided with an extension 59 which is connected to one end of a corrugated longitudinally extensible member or bellows resorted to without departing from the scope and spirit of my invention; hence I do not 40 wish to limit myself strictly to the structure herein set forth, but

60. The opposite end of the bellows 60 is provided with a cap 61 which is pivotally connected to a link 62 which, in turn, is pivoted to a support as at 63. The inner end of the lever 62 is provided with an adjustable 10 weight 64. The outer end of the lever 62 is pivotally connected to a link 65, the lower end of which is provided with a loop 66 through which passes the arm 28. The arrangement is such that so long as the pressure in the 15 pipe 52 and extension 59 does not fall below a predetermined minimum, the arm 28 has freedom of movement within the loop 66. When, however, the pressure in the pipe 52 and extension 59 falls below a predetermined 20 minimum the weight 64 will compress the bellows 60, thus elevating the link 65, which, in turn, will elevate the arm 28 and link 31 to open the circuit and stop the motor. By means of the adjustable weights 30 and 64 the 25 device may be set to open the switch at any suitable predetermined pressure in the bellows.

As a further precaution, the compressor-condenser may be provided with a pipe and 30 safety valve 67 similar to that shown in patent to Bechtold & Mellows, No. 1,276,612, August 20, 1918. This valve will open by excessive pressure and permit the discharge of compressed refrigerant vapor back into 35 the low pressure side of the system.

It will be understood that various changes in the shape, size, proportions, details of construction, and arrangement of parts may be

What I claim is:

1. In an apparatus of the class described, a refrigerant system, a passage for cooling water associated therewith, an electrically actuated valve in said passage, a motor for said system, an electric circuit connecting both the motor and the valve with an electric current supply, a switch in said circuit for opening 45 and closing the same, fluid pressure actuated means mechanically connected to said switch for operating the same, and auxiliary means mechanically connected to said switch for opening it when the pressure in said water 50 passage falls to a predetermined minimum, said auxiliary means operating independently of said fluid pressure means to actuate said switch.

2. In an apparatus of the class described, a refrigerant system, a passage for cooling water associated therewith, an electrically actuated valve in said passage, a motor for said system, an electric circuit connecting both the motor and the valve with an electric current 65 supply, a switch device in said circuit for opening and closing the electric circuit and thereby controlling the valve and the motor, independent actuating means mechanically connected to said switch device and comprising 70 a fluid pressure device responsive to temperature changes and an auxiliary fluid pressure device responsive to pressure changes in the cooling water passage.

In testimony whereof I affix my signature.
JOHN R. REPLOGLE.
